By Xeraltis E. Prezence,
Attorney:

UNITED STATES PATENT OFFICE.

FREDERICK A. STEVENS, OF PROVIDENCE, RHODE ISLAND, ASSIGNOR TO STEVENS AND COMPANY, INCORPORATED, A CORPORATION OF RHODE ISLAND.

MOUNTING.

1,274,806.

Specification of Letters Patent. Patented Aug. 6, 1918.

Application filed October 13, 1917. Serial No. 196,377.

To all whom it may concern:

Be it known that I, FREDERICK A. STEVENS, a citizen of the United States, residing at Providence, in the county of Providence and 5 State of Rhode Island, have invented certain new and useful Improvements in Mountings, of which the following is a specification.

My invention relates to mountings for eye- 10 glasses or spectacles, and more particularly to those of the finger piece type.

The principal purposes of my invention are to insure a smooth movement of the operating levers upon their pivot members; to 15 minimize the friction between the operating springs and the journal portions of the levers; to prevent any weakening of the spring by continued use; to insure free action of the spring; and to attain these ends in a 20 simple and strong structure.

My invention consists, therefore, in the means and mechanism for producing the results above specified substantially as herein- 25 after described and claimed, and as shown in the accompanying drawings forming a part of this specification, and in which—

Figure 1 is a front elevation of a pair of eyeglasses embodying my invention,

Fig. 2, a plan view of one end of the 30 same,

Fig. 3, a section enlarged on line 3—3 of Fig. 2,

Fig. 4, an enlarged section on line 4—4 of Fig. 3, and

Fig. 5, a detail view of one of the annular sections of the sleeve portion.

Like characters of reference indicate like parts throughout the views.

The frame of the eyeglasses or spectacles 40 may be of any form desired for carrying the operative parts. In the construction herein shown 6 is a bridge, having end supports 7 carrying straps 10 and attaching lugs 11 for the lenses 12.

Posts 9 have reduced threaded portions 45 upon their ends engaging threaded perforations 13 in the supports 7; the resultant shoulders 14 upon the posts contacting with the supports. Each operating arm or lever 50 16 has a thumb piece 17 on its forward end, and a nose guard 18 upon its rear end, while in its intermediate portion is an opening 19 to allow the passage of a post therethrough. Integral with the lever is a vertical cylin-

drical flange 20 bounding the hole and surrounding the post as a sliding or running fit. This flange constitutes the lower portion of a sectional sleeve indicated in a general way by 22. This sleeve is completed by an end annulus or ring 24, and one or more rings 25 60 in contact with each other resting against the flange 20. The ring 24 is in slidable contact with the under side of a head 27 on the end of the post provided with a slot 28. All the rings are rotatable upon the post. 65

A helical operating spring is provided for each lever, and the coils thereof embrace the sectional sleeve. In the present instance the coils are equal in number to the rings and flange, but this is not essential. The uppermost coil 30 embraces the ring or section 24; the lowermost coil 31 embraces the flange or section 20; and the intermediate coils 32 engage the intermediate rings 25.

The coil 30 is continued to form an arm 75 34 which bears against the rear of an adjacent strap 10; and the coil 31 is extended into an arm 35 having a bent end 36 engaging the lever 16.

The helical springs induce the guards 18 80 toward each other, while manual compression of the thumb pieces 17 distend the guards to release the structure from the nose. The resultant vibration of the levers imparts to the several coils not only movements of expansion and contraction, but also a circular or rotary movement of varying extent. The lower coils have a greater relative circular or rotative movement than the upper coils. Hence the corresponding annular sections which the several coils embrace have a separate, independent, circular movement of different distances. Thus there is practically no friction between the coils and the sectional sleeve; an easy and 85 even movement of the levers is insured; and all wear upon spring is avoided whereby the life and strength of the latter is prolonged. 90

I claim:

1. In eyeglasses or spectacles, the combination with the frame, of a post on the frame, an operating lever resting against the frame, a sectional sleeve on the lever journaled on the post, a helical spring embracing the sleeve, an arm on the spring engaging the frame, and an arm on the spring engaging the lever. 100
2. In eyeglasses or spectacles, the combi- 105

nation with the frame, of a post on the frame, a head on the post, an operating lever mounted on the frame, a sectional sleeve on the lever journaled on the post engaging the head, a helical spring embracing the sleeve, an arm on the spring engaging the frame, and an arm on the spring engaging the lever.

3. In eyeglasses or spectacles, the combination with the frame, of a post on the frame, an operating lever pivotally mounted on the post adjacent the frame, a sectional sleeve comprising superposed annular sections journaled on the post and supported by the lever, a helical spring surrounding the sleeve comprising coils in individual contact with the different sections, an arm on one end of the spring engaging the frame,

and an arm on the other end of the spring engaging the lever.

4. In eyeglasses or spectacles, the combination with the frame, of a post on the frame, a head on the post, an operating lever pivotally mounted on the post adjacent the frame, a flange on the lever surrounding the post, annular sections loose on the post extending from the flange to the head, a helical spring comprising a series of coils embracing the flange and the sections, an arm on one end of the spring engaging the frame, and an arm on the other end of the spring engaging the lever.

In testimony whereof I have affixed my signature.

FREDERICK A. STEVENS.
